UNITED STATES PATENT OFFICE.

SAMUEL E. BROWN, OF HOUSTON, GEORGIA.

COTTON-CULTIVATOR.

SPECIFICATION forming part of Letters Patent No. 246,069, dated August 23, 1881.

Application filed April 11, 1881. (No model.)

To all whom it may concern:

Be it known that I, SAMUEL E. BROWN, a citizen of the United States, residing at Houston, in the county of Heard and State of Georgia, have invented certain new and useful Improvements in Cotton-Cultivators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The object of my invention is to provide a simple and readily-operated machine for cultivating cotton; and the invention consists in the construction and arrangement of parts, as hereinafter more fully described and claimed.

20 In the annexed drawings, Figure 1 is a plan view, and Fig. 2 is a longitudinal section.

A is a stationary frame provided at its forward end with the tongue B. The frame A is also provided at each end with supports a a and cross-pieces b, through holes in which pass the standards or upward-projecting pins c c of an adjustable frame, C, that is arranged within the stationary frame. The inner adjustable frame, C, is provided with cross-pieces c' c'', that furnish bearings for a revolving shaft, D, which is journaled therein. This shaft carries the blades or choppers E E, and is provided at its forward end with a bevel-gear, e, that meshes with a bevel-gear, f, on the shaft or 35 axle F, that is journaled in the frame A, and to which are attached the wheels F' F'. It will be seen that as the axle F is revolved motion will be communicated to the shaft D so as to operate the blades E.

40 To each side of the frame C are attached the cultivators G G in any convenient manner. In order to raise these cultivators from the ground in moving the machine from one place to another a lever, H, is provided, which is stepped 45 or pivoted in the cross-piece c'', and attached

by means of a chain, h, to the under side of the seat-frame I, in such a manner that the pressure of the driver's foot upon it will raise the frame C and hold the cultivators up from contact with the soil.

The manner in which the frame C is attached to the frame A, by means of the pins c c passing through the cross-pieces b b, enables the frame C to be adjusted in such a position that the gears e f will be thrown out of engagement with each other when it is not desired to operate the cutting-blades E E. When depressed to its lowest point the forward end of the frame C rests on the cross-piece A' and axle F, and is also prevented from becoming detached by the rod d that extends between the rear pins, c c. When the operating parts are in gear the frames A and C are also connected by the strap J on the frame C, engaging with a pin, s, on the tongue B or forward end of the frame A, so that there is a direct draft through the machine that equalizes strain, and when the frame C is lifted the strap J is also lifted from the pin s.

Having thus described my invention, what I claim as new, and desire to secure by Letters Patent, is—

1. In a cotton-cultivator, the main frame A, provided with uprights a, supporting the cross-pieces b, in combination with the inner frame, C, carrying the cultivators G and chopper-shaft D, said frame C being provided with the fixed vertical guides or pins c, passing through holes in cross-pieces b, substantially as set forth.

2. The combination of the outer frame, A, and inner frame, C, having the strap J and pin s, the vertical pins c, cross-pieces b, and lever H, all being constructed as shown, for the purposes set forth.

In testimony whereof I affix my signature in presence of two witnesses.

S. E. BROWN.
